UNITED STATES PATENT OFFICE

JEFFREY JOHN WALLACE, OF AMITE, LOUISIANA, ASSIGNOR TO GULLETT GIN COMPANY, OF AMITE, LOUISIANA, A CORPORATION OF LOUISIANA

AUTOMATIC COTTON PRESS RETAINER CONTROL

Application filed April 30, 1929. Serial No. 359,264.

The invention forming the subject matter of this application comprises an attachment adapted to be connected to the framework of a cotton press and to the press boxes in order to control the rotation of the shaft from which retaining fingers project through slots in the doors of the press to hold down cotton after being tramped as it comes from the cotton gin.

10 The main object of the invention is to provide a locking device for controlling the rotation of a shaft from which retainer fingers project radially through the doors of the cotton press for holding cotton in the press box while it is being ginned and tramped.

Another object of the invention is to provide an attachment which can readily be applied to any of the hand-operated shafts now in common use to control the positioning of 20 the retaining fingers in the press box.

Another object of the invention is to provide a means for automatically releasing the shaft controlling attachment whenever the press box is rotated from position under the 25 trumper to a position over the baling ram.

Other objects of the invention will become apparent as the detailed description thereof proceeds.

In the drawings—

30 Figure 1 is a side elevation of a cotton press provided with my attachments;

Figure 2 is an end elevation of the press, the view being taken on the righthand end of the machine as shown in Figure 1;

35 Figure 3 is a fragmentary and elevation of a press box equipped with this invention, the view being taken from the lefthand end of Figure 1;

40 Figure 4 is a horizontal section taken on the line 4—4 of Figure 1; and

Figure 5 is a perspective view of the locking device forming part of this invention.

As shown in Figure 1, the invention comprises a shaft 1, rotatably mounted in bearings 2, 3, 4 and 5, suitably secured to a door 6 of the press box 7. The shaft 1 extends perpendicularly across slots 8, 9, 10 and 11 formed in the door 6; and retaining fingers 50 13, 14, 15 and 16 extend radially from the

shaft 1 through the said slots 8, 9, 10 and 11, respectively.

The fingers are rigidly connected to the shaft 1 in any suitable manner; and the end of the shaft 1 projects beyond the outer end 55 17 of the press box 7. Fixedly secured on the shaft 1 where it projects beyond the end 17 of the press box is a weight 18 having a face 19 adapted to contact with a trip 28 formed on the end of a shaft 21 which is journaled 60 in bearings 22, suitably secured to the end 17 of the press box.

The sleeve 23 is fixed to shaft 21 between the bearings 22; and this sleeve is provided with a lug 24 adapted to contact with the 65 end 17 and form a stop to hold the said sleeve in a predetermined position required for operation of a trip plate 25 which extends from said sleeve and terminates in a cam member 26. 70

The cam member 26 is preferably integral with the trip plate 25 and the connection between the two is reinforced by a rib 27. Each end of the shaft 21 has suitably secured thereto a trip lug 28, which extends radially from 75 the said shaft and is in rotatable contact with the outer side of adjacent bearing 22 to secure the shaft 21 against longitudinal movement in its bearings 22.

When the trip plate 25 is in normal position, as shown at the lefthand end of Figure 1, the trip lug 28 is in the path of swing of the weight 18 and prevents rotation of the shaft 1 in order to hold the fingers 13, 14, 15 and 16 against rotation in an upward direction 80 in the press box 7 during the tramping of the cotton therein. As will be apparent from the drawings, downward movement of the said fingers is always permitted because there is nothing to prevent rotation of the 85 weight 18 away from the trip lug 28.

When the press is swung around to bring the press box 7 over the baling ram 29, the curved edge 30 of the cam plate 26 slides over the edge 31 of a plate 32, secured to a column 33 forming part of the framework of the press. As will be apparent from Figures 1 and 4, contact between the cam plate 26 and the plate 32 raises the plate 26 and causes rotation of the shaft 21 to move the 90 100

trip lug 28 out of the path of swing of the weight 18.

When the cam plate 26 is positioned as shown at the righthand end of Figures 1 and 5 4, the weight 18 is free to swing in either direction and the fingers 13, 14, 15 and 16 are free to rotate upwardly in the press box 7 as the cotton is forced upward by the baling action of the ram 29.

10 The upper edge of the door 6 is provided with a ledge which acts as a stop engageable with the platform 34 in order to support the door 6 in such position as to prevent the swinging weight 18 coming in contact with the platform.

As will be apparent from the disclosure so far, this invention converts the ordinary hand-control pressure finger mechanism into an automatically operable device which 20 requires no attention from the operator of the press to which the invention may be applied.

The device does not depend for its operation upon pressure from within the box. As is shown in Figures 1 and 2, when cotton is 25 fed into the box 7 from the top of the trumper it pushes the cotton already in the box down past the fingers 13, 14, 15 and 16, the weight 18 swinging outwardly of the door 6 to permit this rotation of the fingers. As soon as 30 the trumper block rises from the inside of the box 7, the cotton also rises in the box and impinges against the retaining fingers which are then prevented from rotation upwardly in the box by engagement of the rear edge 19 of weight 18 with the trip lug 28.

When the trip lug 28 is rotated out of the path of swing of the weight 18, the shaft 1 is free to rotate in either direction. This condition always exists when the press box 40 is rotated into its position above the baling ram 29, in which position the pressure on the cotton is always upward and the retaining fingers must be moved out of the way of the cotton being baled.

45 Since the finger retaining shafts are the same on all four doors of the cotton press, and since all the parts connected thereto are structurally identical with the corresponding parts previously described, the corresponding elements on all the doors are designated by the same reference numerals as have been applied to the elements so far described.

While I have shown the locking element of 55 this device as mounted on the outer ends of the press boxes to cooperate with an operating plate fixed on an outer part of the supporting framework, it is to be understood that the invention is not to be considered as 60 in any way limited to this particular location of the cooperating parts. The parts named may be just as readily mounted on the inner doors of the press boxes to cooperate with a plate fixed to the supporting column 65 between the two press boxes; and the claims

of this application will be drawn accordingly to cover the invention broadly.

What I claim is:

1. In a cotton press operating in co-ordination with a trumper and baling ram, the combination with a press box having a door, a shaft journaled on said door, a finger fixed to said shaft and normally extending into said press box so as to intersect the line of transmitted force from the trumper or the 75 baling ram, a stop normally engaging said shaft and preventing oscillation thereof beyond its normal position in one direction but permitting oscillation of said shaft in the opposite direction, and means for releasing said stop from its normal engaging position. 80

2. In a cotton press, operating in co-ordination with a trumper and baling ram, the combination with a press box having a door, a shaft journaled on said door, a finger fixed to said shaft and normally extending into said press box so as to intersect the line of transmitted force from the trumper or baling ram, a weight or said shaft normally maintaining said finger in extended position through gravity, a stop normally engaging said shaft and preventing oscillation thereof beyond its normal position in one direction but permitting oscillation of said shaft in the opposite direction, and means for releasing said stop from its normal engaging position. 90 95

3. In a cotton press as claimed in claim 2, the stop and releasing means comprising a shaft carrying the stop inter-engaging with said first named shaft and a cam on said second named shaft engageable with a fixed element for tilting said second named shaft and releasing said stop. 100

4. In a cotton press operating in co-ordination with a trumper and baling ram, the combination with a press box rotatable on an extraneous axis to a position from beneath said trumper to above said baling ram, said press box having a door, a shaft journaled on said door, a finger fixed to said shaft, means for normally maintaining said finger extended into said press box, so as to intersect the lines of transmitted force from the trumper or the baling ram, a stop normally engaging said shaft and preventing oscillation thereof beyond its normal position in one direction but permitting oscillation of said shaft in the opposite direction, and means for releasing said stop from its normal engaging position, actuatable by means which said releasing means engages when said press box assumes position above said baling ram. 110 115 120

5. In a cotton press operating in co-ordination with a trumper and baling ram, a combination with a press box rotatable upon an extraneous axis from a position beneath said trumper to a position above said baling ram, said press box having a door, a shaft journaled on said door, a finger fixed to said 125 130

shaft, a weight on said shaft normally maintaining said finger extended into said press box so as to intersect the line of transmitted force from the trumper or the baling ram, a 5 stop normally engaging said shaft and preventing oscillation thereof beyond its normal position in one direction but permitting oscillation of said shaft in the opposite direction, and means for releasing said stop 10 from its normal engaging position, comprising a second shaft on said press box upon which said stop is mounted, and a cam on said second named shaft engageable with a fixed element when said press box assumes a position 15 above said baling ram, for tilting said second named shaft and thereby releasing said stop.

6. In a cotton press the combination with a press box having a hinged door provided 20 with a slot, a shaft rotatably mounted on said door and having a part projecting beyond one edge of the door, a finger extending laterally from said shaft, a weight fixed to said part and depending therefrom to hold 25 said finger projecting through said slot substantially perpendicularly to the inside of said door, a second shaft rotatably mounted on one end of said box and having a trip finger movable by rotation of the second shaft 30 into and out of engagement with said weight to lock the first named shaft against rotation by upward pressure on said finger when the door is closed, means to rotate the second shaft on said end, and stop means on said 35 second shaft to limit the rotation of said second shaft relative to said end.

7. In a cotton press a supporting frame, a press box rotatably mounted on said frame and having a hinged door provided with a 40 slot, a shaft rotatably mounted on said door and having a part projecting beyond one edge of the door, a finger extending laterally from said shaft, a weight fixed to said part to hold said finger projected through said 45 slot perpendicularly to said door when the door is closed, means on one end of said press box and adjustable into and out of engagement with the first named means to lock the shaft against rotation by upward pressure 50 against said finger, and cooperating means connected to said framework and to the second named means for releasing said shaft when the press box is moved to a predetermined position in said frame.

55 8. In a cotton press, a frame, a press box rotatably mounted on said frame and having a hinged door provided with a slot, a shaft rotatable on said door and having a part projecting beyond one edge thereof, a finger extending laterally from said shaft, a weight 60 fixed on said part to hold the finger projected through said slot perpendicularly to the door when the door is closed, and gravity controlled means adjustable into and out of engagement with said weight to lock the shaft 65

against rotation by upward pressure against said fingers.

9. In a cotton press, a frame having a pair of vertical columns, a press box rotatably mounted on said frame and having a hinged door provided with a slot, a shaft rotatable on said door and having a part projecting beyond one edge thereof, a finger extending laterally from said shaft, a weight fixed on said part to hold the finger projected through 70 said slot substantially perpendicularly to the door when the door is closed, gravity controlled means adjustable into and out of engagement with said weight to lock the shaft against rotation by upward pressure against 75 said finger, and means on one of said columns adapted to contact with said gravity controlled means when the press box is rotated on said frame to a predetermined position and operate said gravity control means 80 to release said shaft.

In testimony whereof I affix my signature.
JEFFREY JOHN WALLACE.
